UNITED STATES PATENT OFFICE.

GAZZAM GANO, OF CINCINNATI, OHIO.

DESIGN FOR THERMOMETER-BACKS.

Specification forming part of Design No. 7,915, dated December 8, 1874; application filed July 27, 1874.
[Term of Patent 7 years.]

To all whom it may concern:

Be it known that I, GAZZAM GANO, of Cincinnati, in the county of Hamilton and State of Ohio, have invented a Design for Thermometer-Backs, of which the following is a specification:

My invention consists in making thermometer-backs with pictorial representations, indicative of the hazards of underwriting, as superinduced by high or low degrees of temperature.

The illustration, forming a part of this specification, shows, at bottom, a shipwreck in the ice, exemplifying the hazards of marine underwriting as superinduced by a low degree of temperature, and, at top, burning buildings, illustrating hazards of fire-underwriting as superinduced by a high degree of temperature. The pictures next to the bottom are of scenes in the frigid or the colder part of the temperate zones. Those next above show on one side a

summer scene in the temperate zone, and on the other a building set on fire by lightning. The pictures next above are tropical and mountain scenes, including a volcano.

The pictures may be varied in their details, and will be properly colored to render them more attractive, as well as more effective in conveying the desired impressions.

The thermometer-scale may be printed directly on the card or other pictorial back, or it may be engraved on a metallic plate to be attached to the pictorial back.

I claim as new—

The design for a thermometer-back, consisting of pictorial representations indicative of hazards of underwriting, substantially as set forth.

GAZZAM GANO.
